DESIGN FOR A GRAVE ENCLOSURE

August Steindl, New York, N. Y.

Application August 28, 1940, Serial No. 94,686

Term of patent 7 years

To all whom it may concern:

Be it known that I, August Steindl, a citizen of the United States and a resident of New York city, county of Queens, and State of New York, have invented a new, original, and ornamental Design for a Grave Enclosure, of which the following is a specification, reference being had to the accompanying drawing, forming part thereof.

sure, partly illustrated in dotted lines showing my new design;

I claim:

The ornamental design for a grave enclosure, substantially as shown.

AUGUST STEINDL.
